DOUBLE ACTING THERMOSTATIC
MECHANISMJoseph A. Cerny, Cleveland, Ohio, assignor to The
Titan Valve and Manufacturing Company,
Cleveland, Ohio, a corporation of Ohio

Application December 22, 1937, Serial No. 181,115

2 Claims. (Cl. 236—48)

This invention relates to improvements in thermostatic control mechanism and, more particularly, to a control wherein a single thermostatic element actuates a plurality of control members.

One of the objects of the present invention is to provide mechanism for actuating two or more control members from a single thermostatic means and a particular application of this control mechanism is the opening of two valves successively during movement of the thermostatic element in one direction.

A particular feature of the present invention is the opening of a limited capacity or pilot valve to a fuel burner upon demand of the thermostatic element followed by the opening of a large capacity or main valve after a time interval under the control of the thermostatic element.

Other features of the present invention have to do with the specific arrangement of the parts whereby a small number of parts simply arranged bring about the results set forth. These features will be better understood from the accompanying specification and drawing and the essential features will be summarized in the claims.

In the drawing, Fig. 1 is a central longitudinal section through a device embodying my invention showing the parts with both valves closed; Fig. 2 is a partial view of the mechanism shown in Fig. 1 showing the parts with one of the valves open; Fig. 3 is a similar view showing the parts with both valves open; Fig. 4 is a partial transverse sectional view taken along the line 5—5 of Fig. 2; while Figs. 5 and 6 are side elevations of the levers shown in Figs. 1 to 3.

Certain features of my invention are applicable where the thermostatic device actuates a plurality of control members whether these members be switches, valves or any other suitable device for controlling a desired operation. I have illustrated my invention as applied to the actuation of two fluid controlled valves where both control a common supply. I do not desire to be limited, however, in this application of my device as it will be readily understood that they might control different sources of power or fuel within the limits of the appended claims.

In the embodiment of my invention shown here as exemplary, I have provided a casing 10 having fluid inlet ports 11 and 12 and an outlet port 13. Valves 14 and 15 control the ports 11 and 12 respectively and are normally spring pressed to closed position. Referring to Fig. 4 the fluid supply conduit enters the casing 10 at

15 and beyond this point the fluid stream is divided by partition 10a providing an upper fluid inlet chamber 16 and a lower fluid inlet chamber 17. The fluid supply to chamber 16 is by way of a restricted port 18 and the supply to chamber 17 is by way of the large port 19. Preferably, adjusting screws 20 and 21 are provided for controlling the flow through ports 18 and 19, respectively, and sealing screws 22 cover the adjusting screws. I have hereinafter referred to 11 as a minor inlet port and 12 as a major inlet portion and to valve 14 as a minor valve and to valve 15 as a major valve. By these terms I mean to imply that port 11 and valve 14 supply a small amount of gas while port 12 and valve 15 supply the main or large supply of gas. This language is used to cover any structure by which this is accomplished because obviously it may be attained either by valve design or by restriction of passageways as in the present embodiment.

One of the applications of a structure of the general nature here shown is in water heaters or the like where a burner supplies heat to the water reservoir and the burner is housed in a combustion chamber which with its flue connections is unable to carry off the products of combustion when the parts are cold. In such an installation a conduit connects the fluid outlet 13 with the burner of the water reservoir and a thermostatic element 23 is located in the water reservoir. In such a system, when the thermostat 23 demands heat, my improved device is arranged to first open valve 14 to supply a limited amount of fuel to the burner so as to heat up the parts, after which the thermostatic device opens valve 15 permitting the full supply of fuel to the burner which can then be accommodated because the flue and associated parts have been previously heated. In the device illustrated, the thermostatic element is of well known type comprising a tube 23a having relatively large coefficient of expansion and a rod 23b of material having a relatively small coefficient of expansion. These two are fastened together at 23c so that when the tube is cold and contracts, the rod 23b is moved toward the left, and when the tube is heated and expands, the rod moves to the right as viewed in the various drawings. The left end of rod 23b enters the casing 10 through an opening which is sealed at 24. The device at 25 is a well known arrangement for adjusting the temperature range of the thermostatic element.

Mounted within the casing 10 are a main lever

26 and a snap lever 27 fulcrumed on the casing at 28 and 29, respectively. This places the levers alongside each other with the free end of each lever extending toward the fulcrum of the other. 5 In the device shown the fulcrums are open-knife edges abutting suitably formed projections on the casing. A tension spring 30 is connected between the free ends of the levers. The thermostatic element engages lever 26 at 31 and the 10 arrangement of the parts is such that upon heating and cooling of the thermostatic element, lever 26 oscillates so as to carry the end 32a of spring 30 back and forth to opposite sides of fulcrum 29. Thus the tendency of spring 30 15 is in the position of Fig. 1 to hold lever 27 toward the right and in the position of Figs. 2 and 3, the same spring moves lever 27 toward the left or counterclockwise. The effect of spring 30 obviously is to hold both levers in position against 20 their fulcrums and to hold lever 26 against rod 23b.

The valve 15 is provided with an extending portion 15a calculated to open valve 15 at the proper time as will later appear.

25 The construction of levers 26 and 27 will better appear from Figs. 5 and 6, respectively. Lever 26 tapers toward its lower end where it is provided with a notch 26a to receive the end 32a of spring 30. Lever 27 is provided with an opening 27a to receive the upper end of spring 30 and is bifurcated at its lower end providing a pair of knife edges 27b to coact with the fulcrum 28. The central opening of lever 27 permits the operation of lever 26 and spring 30.

30 The operation of the device is as follows: With the parts in the position of Fig. 1, it will be understood that the thermostat 23 is satisfied, that is, the water in the hot water reservoir of the heater has arrived at a predetermined temperature and all fuel to the burner is shut off. Upon the cooling of thermostat 23, rod 23b moves toward the left, carrying lever 26 in a clockwise direction about fulcrum 28 until the point 26a passes to the left of fulcrum 28 carrying 35 the axis of spring 30 to the opposite side of the fulcrum, whereupon lever 27 moves counterclockwise with a snap action opening valve 14 as shown in Fig. 2. Fuel is then supplied to the burner through the restricted opening 16, thus 40 heating up the combustion chamber and flue. The heat thus supplied to the water reservoir is insufficient to change the action of thermostat 23 which continues to contract, carrying lever 26 further in a clockwise direction until 45 the free end of lever 26 (or the end of spring 30 lying alongside the end of the lever) engages the portion 15a of valve 15. This slowly opens valve 15 supplying more and more fuel to the burner of the water heater until the thermostat 50 23 is satisfied sufficiently to reverse the movement of rod 23b. Thereupon the heating of the thermostat causes 23f to return toward the right which will cause a gradual closing of valve 15 until it is fully closed, after which the lever 55 26 will return to the position of Fig. 1, causing

a clockwise movement of snap lever 27 and permitting valve 14 to close with a snap action due to its biasing spring.

It will be noted that the lever arm of lever 26 effective to actuate valve 15 is approximately 5 ten times the lever arm between fulcrum 28 and point 31 where the thermostat engages the lever. This gives a considerable multiplication of the thermostat movement when actuating valve 15.

It results from my improved control apparatus that upon demand for heat from the thermostat, the burner is quickly supplied with a predetermined small amount of fuel to heat up the parts, followed by the gradual addition of fuel supply from the main valve which is added 15 slowly so as to progressively build up the flame at the burner until the action of the thermostat is reversed, after which the main supply of fuel is gradually cut off from the burner and as the thermostat reaches its limiting or satis- 20 fied position the last increment of fuel is cut off with a snap action.

What I claim is:

1. Control valve mechanism of the class described, comprising a casing having a chamber 25 provided with major and minor fuel inlet openings and an outlet, a valve controlling each opening, main and snap action levers fulcrumed in said chamber and lying alongside each other with the free end of each extending toward the 30 fulcrum of the other, a spring connecting said levers, a thermostatic element directly engaging said main lever, said main lever being adapted to engage and operate said major valve with graduating effect, and said snap action lever 35 being adapted to engage and suddenly operate said minor valve, said main lever being arranged upon heat demand of said thermostatic element to move its spring connection past said snap action lever fulcrum to a minor valve operating 40 position before said main lever engages said major valve.

2. Control valve mechanism of the class described, comprising a casing having a chamber 45 provided with major and minor fuel inlet openings and an outlet, major and minor valves respectively controlling said openings, a main lever fulcrumed in said chamber and adapted to engage and operate said major valve, a thermostatic element directly engaging said main lever, a snap action lever adapted to engage and operate said minor valve, a spring having one end carried by said snap action lever, said snap action lever having a fulcrum point and having its free end extending toward said main lever fulcrum, said spring having a connection point at its other end, one of said points being fixed and the other of said points being on said main lever, and said main lever being arranged upon heat demand of said thermostatic element to move the said other point located on the main lever past the said fixed point to minor valve operating position before said main lever engages said major valve.
